BOTTLE HOLDER AND CARRIER

Grant M. Acton, Arkansas City, Kans., assignor
to Acton Manufacturing Company, Inc., a cor-
poration of Kansas

Application March 20, 1948, Serial No. 16,032

4 Claims. (Cl. 224—48)

1

This invention relates to bottle holders and carriers and more particularly to a device for holding and carrying bottles used for beverages such as soft drinks and the like, the principal objects of the invention being to provide a bottle holder and carrier adapted for use with bottle handling machines such as automatic bottle case unloaders and for transporting bottles of beverage as when carrying them from retail stores.

There have been various types of bottle carriers made of paper, fiberboard, wire and sheet metal for carrying bottled beverage from retail stores to the customer's home. Such carriers are used for taking empty bottles back to the store where the empties are removed and full bottles from cases or coolers placed in the carrier for the purchaser to again carry home. The empties are placed in wooden cases and returned to the bottling plant where they are removed from the cases by automatic bottle case unloaders and processed. The cases are then moved through an automatic loading machine which places filled bottles into the cases.

Further objects of the present invention are, therefore, to provide a carrier of such size and shape that a plurality of same fit in the usual wooden case which is minus the conventional separators whereby the bottles need only be removed from the carrier at the bottling plant and in the home for use; to provide a carrier structure characterized by the absence of projecting ribs or fastening devices whereby complete engagement of the side and end walls thereof with the case and adjacent carriers is obtained; to provide a carrier of suitable material forming a rigid structure capable of continued use in automatic machines and for all transportation, storage and cooling of the bottled beverage; to provide a bottle carrier in which several bottles may be carried at one time; to provide a bottle carrier adapted for quick and easy placing and removing of bottles, said bottles being held in semirigid position avoiding breakage when the carriers are handled by automatic equipment, and supporting said bottles in such a manner as to eliminate bottle slippage when a case containing four carriers is picked up by a bottle as is commonly done by case handlers in the industry; to provide a carrier and bail structure in which the bail is adapted for engagement with suitable holddowns or automatic bottle case unloaders to transmit pressure to the body of the carrier during removal of the bottles therefrom; to provide a

2

carrier and bail therefor which permits telescoping of said bail allowing the filled carriers to be stacked; and to provide a carrier consisting of relatively few pieces that may be quickly and easily manufactured and assembled into a compact, sturdy and efficient device for carrying and holding beverage bottles during transportation and use with automatic machines in bottling plants.

10 In accomplishing these and other objects of the present invention, I have provided improved details of structure, the preferred forms of which are illustrated in the accompanying drawings, wherein:

15 Fig. 1 is a perspective view of the improved bottle carrier.

Fig. 2 is a transverse sectional view through the carrier taken on the line 2—2, Fig. 1.

20 Fig. 3 is a partial longitudinal sectional view taken on the line 3—3, Fig. 1.

Fig. 4 is a disassembled perspective view of the improved bottle carrier.

Referring more in detail to the drawings:

1 designates a bottle carrier and holder 25 generally consisting of a body member 2, a bottom member 3, and a top spacer 4. The body member is cut from a single piece of sheet metal or the like and formed by suitable dies. The central portion of the body member forms a horizontal partition 5 of suitable size to accommodate the desired number of bottles, the illustrated structure being adapted to receive six bottles, two rows in width and three rows in length, said partition being cut and formed to provide apertures 6 for receiving said bottles, the edges of said apertures being turned downwardly to form flanges 7 to provide additional surface contact between the partition and the bottles received therein. The apertures 6 are suitably arranged to space the flanges 7 of the respective apertures. Portions arranged at the ends of the partition 5 are turned upwardly as at 8, substantially tangentially with the end apertures 6 to form flanges 9 and 10, said flanges being substantially one-half the width of the partition and having suitably spaced slots 11 therein for use in assembling the device as later described.

The body member includes sides 12 and 13 preferably integral with the partition 5. The flat sheet of which the body member is formed is bent upwardly as at 14 and 15 on longitudinal lines substantially tangential with the outside portion of the apertures 6 to form the side members 12 and 13. Said side members are longer

than the partition sides and are bent as at 16—17 and 18—19 respectively to form end portions 20, 21, 22 and 23 cooperating to form the ends of the carrier as later described. The upper edges of the sides and end portions are turned inwardly as at 24 to form flanges 25, folded against the inner surface 26 of said portions. The lower edges of the end portions and sides adjacent the ends of the lines 14 and 15 are turned inwardly as at 27 to form flanges 28, folded against the inner surface 26 of said members. The flanges 25 and 28 form rounded upper and lower edges and provide a finished appearance eliminating sharp edges and stiffening the sides and end portions to provide suitable rigidity therein. Each of the end portions 20, 21, 22 and 23 is provided with inwardly struck tangs 29 and the side and end portions are provided with horizontal slots 30 spaced slightly below the lower edge of the flanges 25 for assembling the structure as later described.

The bottom member 3 is bent as at 31 and 32 forming a horizontal bottom portion 33 and upwardly extending end members 34 and 35, the height of said end members being such that the upper edges 36 thereof are adapted to engage the lower edge of the flanges 25 and the full height from the bottom of the upper edge of the side member is substantially the same as the inside height of the side walls of a conventional wooden case. Each of the end members 34 and 35 is provided with inwardly struck portions 37 of substantially the same width as the width of the flange 28 whereby the end members 34 and 35 are adapted to lie against the inner face of the end portions 20, 21, 22 and 23 of the side members. The longitudinal edges of the bottom member 3 are turned inwardly to form flanges 38 and 39 tightly folded against the inner faces of the respective portions for stiffening and strengthening the bottom member and eliminating any exposed sharp edges as well as enhancing the appearance of the finished product. The upper end portions of the bottom member are provided with a plurality of slots 40 adapted to register with the tangs 29 on the end portions of the side members for assembling the respective parts of the carrier as later described.

A reinforcing rib 41 is preferably arranged along the longitudinal center of the bottom portion 33, said ribs preferably terminating short of the end portions 34 and 35. The ribs may be formed in any suitable manner as by forming same in the bottom member. In the structure illustrated, said rib consists of a strip of sheet metal bent as at 42 on the longitudinal center thereof to provide downwardly extending spaced legs 43 and 44, the lower ends of said legs being bent as at 45 to form laterally extending flanges 46 extending toward the side edges of the bottom portion 33. Formed in the rib 41 are spaced bosses 47 preferably frustro-conical in shape and slightly higher than the rib. The upper ends of the bosses are provided with flat faces 47' forming seats which align with and cooperate with a bail on the carrier as later described. The rib is suitably secured to said bottom portion 33 by any suitable manner, for example the flanges 46 are provided with slots 48 adapted to align with tangs 49 pressed upwardly from the bottom 33, said tangs extending through the slots and being flattened against the flanges 46, this flattening process preferably bending a portion of the flanges into the openings 50 formed in the bottom portion upon the cutting and bending of the 75

tangs therefrom. This assembly forms interlocking portions which prevent any movement of the respective parts.

The top spacer is cut from a single piece of sheet metal or the like and formed by suitable dies, said spacer consisting of a horizontal panel 51 substantially the same size as the partition 5, the side edges of said spacer being turned upwardly as at 52 to form upwardly extending flanges 53 and 54, said flanges being adapted to be inserted between the flanges 25 and the inner face 26 of the side portions of the side members and engage the inner surface of the bend 24 thereof. In the same manner the end edges of the spacer are turned upwardly as at 55 to form upwardly extending flanges 56 and 57 adapted to be inserted between the flanges 25 and the inner face of the end portions of the side members and engage the inner surface of the bend thereof. The horizontal panel is cut and formed to provide apertures 58 of substantially the same size and in alignment with the apertures 6 in the partition 5, said apertures 58 and 6 cooperating for receiving and supporting bottles. The edges of the apertures 58 are turned downwardly to form flanges 59 to provide additional surface contact between the top spacer and the bottles received in the carrier. The edges of each of the apertures 58 are preferably provided with recesses 59' arranged substantially tangentially of the respective apertures and parallel with the sides and ends of the carrier. This structure provides four recesses for each aperture whereby spring fingers on automatic bottle case loaders may engage in said recesses to aid in guiding the bottles into the respective apertures, the recesses being of suitable width to accommodate the width of the fingers. Tangs 60 are preferably cut in the flanges 53, 54, 56 and 57 and project outwardly from the horizontal panel 51 in alignment with the slots 30 for assembling the parts as later described.

The carrier is provided with a handle or bail formed of wire or the like of suitable size and stiffness to withstand longitudinal pressure on the members thereof without any bending. The bail consists of a bar member 61, the ends of said bar member being curved downwardly as at 62, the curve being substantially an ogee curve and terminating in downwardly extending vertical members 63, said members 63 being spaced substantially the same as the spacing between the bottle apertures 58 and 6, whereby said vertical members are slidably mounted in apertures 64, arranged on the longitudinal center of the top spacer 4 and are equally spaced from the geometric center of said panel for equal distribution of the weight on said bail, said apertures 64 also being in vertical alignment with the bosses 47 in the rib 41. In order to provide additional support for the bail and top spacer, a reinforcing member 65 is secured thereto. Said reinforcing member preferably consists of sheet metal, consisting of a horizontal wall 66 provided with upwardly extending flanges 67 of suitable size to substantially lie between the flanges 59 in the top spacer. The flanges 67 are shorter in height than the flanges 59 whereby the wall 66 is parallel with the panel 51 and is arranged above the lower edge 68 of the flanges 59, the edges 68 being turned inwardly to crimp the reinforcing member in place. The wall 66 of the reinforcing member is provided with an aperture 69 in alignment with the aperture 64 and adapted to slidably mount the vertical member 63 of the bail.

The apertures 64 and 69 are of such size that there is sliding engagement between said apertures and the vertical member 63. To provide further support for the vertical members, the panel 51 and wall 66 are provided with upwardly and downwardly struck portions 70 and 71 respectively substantially conical in shape whereby the apertures 64 and 69 have greater spacing than the panel 51 and wall 66, this spaced engagement with the vertical member 63 providing adequate support for the bail. The vertical members 63 of the bail are provided with lugs 72 adapted to be moved into engagement with the lower face of the downwardly struck portion 71 to support the weight of the bottles and carrier when being carried by the bail. The vertical members 63 are of such length that when the lugs 72 are in engagement with the downwardly struck portions 71 of the reinforcing member 65, the bar member 61 is above the caps of the bottles to provide sufficient clearance between said caps and bar member for the insertion of the hand of a person to permit the carrier to be transported without danger of striking the hand or fingers on the tops of said bottles. The relationship of the length of the vertical members and the other portions of the carrier are such that when the bail is moved downwardly in telescoped position, the lugs 72 pass through apertures 73 in the partition 5 and engage the faces 47 of the bosses 47 and the bar 61 of the bail lies below the upper ends or caps of the bottles. The bottoms of the lugs 72 are flat to provide substantial supporting engagement between the lugs and the faces 47' tending to maintain the lower ends of the legs 63 centered thereon when downward pressure is applied to the handle. The height of the bosses 47 and bail is such that when the lugs engage the faces 47' the bar member 61 is accurately positioned below the tops of the bottles in the carrier and in position for engagement with a suitable device on an automatic bottle case unloader to apply pressure to the bosses 47 holding the carrier down as bottles are removed by the unloading devices in the machine.

In assembling a carrier of parts constructed as described, the reinforcing member 65 is arranged between the flanges 59 and the top spaces 4 with the apertures 64 and 69 in alignment. The lower edges 68 of the flanges 59 are then crimped to anchor the reinforcing member in place. The vertical members 63 of the bail are then inserted into the apertures 64 and 69 and moved therethrough and the lug 72 formed on the lower ends of said vertical members. The top spacer is now inserted between the side members 12 and 13 and the flanges 53 and 54 arranged between the flanges 25 and the face 26 of said side members with the tangs 60 extending through the slots 30. The tangs are then tightly folded over and pressed against the outer faces of the sides 12 and 13 forming a depression therein whereby the tang does not project beyond the faces of the sides. The bottom member 3 is then applied in such a manner that the end portions 34 and 35 are arranged between the end portions 20-22 and the flange 9, and the end portions 21 and 23 and the flange 10, with the slots 11 and 40 in alignment with the tangs 29. The end portions 20, 21, 22 and 23 are then moved whereby the tangs extend through the slots and said tangs tightly folded over and pressed whereby the portion of the metal adjacent the slots over which the ends of the tangs lie is pressed into the opening formed in the cutting of the tangs from the respective

parts of the device. This forms a completed carrier as illustrated in Fig. 1 adapted to carry a plurality of bottles of beverage, the particular carrier illustrated being adapted for six bottles. The dimensions of the respective parts of the carrier are such that the bottles substantially engage the flanges 7 in the horizontal partition, flanges 59 in the top spacer and the flanges 25 and 28 on the side and end portions of the side members, the lower portions of the bottles being held against contact by the engagement with the respective portions of the carrier, and the bottom of each bottle will rest on the flanges 38, 39 and 46 of the bottom portion 33 and rib 41.

It is believed obvious that I have provided a bottle holder and carrier of rigid structure, capable of holding a plurality of bottles which may be easily removed and inserted in said carriers and particularly adapted to fit in wooden cases and for efficient use in automatic case unloaders and case loading machines, the telescoping bail and associated carrier structure functioning with the case unloader machine to hold the carrier and facilitate removal of the bottles. The bail also permits stacking of the carriers when filled with bottles and provides efficient transportation of the carrier and bottles without danger of striking the hand on said bottles.

What I claim and desire to secure by Letters

Patent is:

1. A bottle holder of the character described for use with automatic bottle case unloaders including, a bottom, an upper spacer member above the bottom, said upper spacer having a plurality of apertures for receiving and substantially engaging bottles, a lower spacer member intermediate the upper spacer and bottom, said lower spacer having apertures in alignment with the apertures in the upper spacer, side members on the lower spacer and extending upwardly therefrom, end members on the side members, means securing the upper spacer to the end members, means securing the bottom, end members and lower spacer together, a handle having spaced portions slidably mounted in the upper spacer, and spaced seats on the bottom in alignment with said handle portions and adapted to be engaged thereby when the handle is at the lowermost position below the tops of bottles contained in the carrier and in position to be engaged by hold-down members on an automatic bottle case unloader for transmitting pressure from said members to the seats for holding the carrier during removal of bottles therefrom.

2. A bottle holder and carrier of the character described for use with automatic bottle case unloaders including, a bottom, end members on said bottom and extending upwardly therefrom, an upper spacer member above the bottom, said upper spacer having a plurality of apertures for receiving and substantially engaging bottles, a lower spacer member intermediate the upper spacer and bottom, said lower spacer member having apertures in alignment with the apertures in the upper spacer, side members on the lower spacer and extending upwardly therefrom, end portions on the side members overlying the end members, means securing the upper spacer to the end portions, means securing the bottom, end portions and lower spacer together, a handle, spaced legs on said handle slidably mounted in the upper spacer to position the handle below the top of the bottles and in position to be engaged by hold-down members in an automatic bottle case

unloader; seats on the bottom in alignment with the handle legs, said legs engaging said seats when the handle is in lowermost position for transmitting pressure from the bottle unloader to hold the carrier down during removal of bottles therefrom, and means on the handle legs engageable with the upper spacer for supporting the bottle carrier when the handle is in its uppermost position.

3. A bottle holder of the character described for use with automatic bottle case unloaders including, a bottom, an upper spacer member above the bottom, said upper spacer having a plurality of apertures for receiving and substantially engaging bottles, side members, end members on the side members, means securing the upper spacer to the side and end members, means securing the bottom to the end members, a handle having spaced portions slidably mounted on the upper spacer, and spaced seats on the bottom in alignment with said handle portions and adapted to be engaged thereby when the handle is at the lowermost position below the tops of bottles contained in the carrier and in position to be engaged by holdown members on an automatic bottle case unloader for transmitting pressure from said members to the seats for holding the carrier during removal of bottles therefrom.

4. A bottle holder of the character described for use with automatic bottle case unloaders including, a bottom, an upper spacer member above the bottom, said upper spacer having a plurality of apertures for receiving and substantially en-

gaging bottles, side members, end members on the side members, means securing the upper spacer to the side and end members, means securing the bottom to the end members, a handle having spaced vertical portions, said upper spacer having spaced openings between the apertures for slidably mounting the spaced vertical portions of the handle, a panel spaced below the upper spacer and secured thereto, said panel having openings aligned with the vertical handle portion receiving openings in the upper spacer for providing spaced supports for said vertical handle portions, and means on the lower ends of the vertical handle portions adapted to engage the bottom when the handle is at the lowermost position below the tops of the bottles contained in the carrier and in position to be engaged by the holdown members on an automatic bottle case unloader for transmitting pressure from said members to the bottom for holding the carrier during removal of bottles therefrom.
